CLAIM

We claim the ornamental design for an animal feed tub cover, as shown and described.

DESCRIPTION

Relates to design patent application U.S. Ser. No. 29/534, 874 filed Jul. 31, 2015, the content of which is incorporated by reference herein in its entirety. This application also relates to a non-provisional patent application U.S. Ser. No. 14/815,488 filed Jul. 31, 2015, the content of which is incorporated by reference herein in its entirety.

FIG. 1 is an isometric view of a first animal feed tub cover showing the new design;

FIG. 2 is a top view thereof;

FIG. 3 is a side view thereof;

FIG. 4 is an isometric view of a second animal feed tub cover showing the new design;

FIG. 5 is a top view thereof;

FIG. 6 is a side view thereof;

FIG. 7 is an isometric view of a third animal feed tub cover showing the new design;

FIG. 8 is a top view thereof;

FIG. 9 is a side view thereof.

FIG. 10 is an isometric view of a fourth animal feed tub cover showing the new design;

FIG. 11 is a top view thereof; and,

FIG. 12 is a side view thereof.

The broken lines in the figures represent portions of the feed tub cover which are not part of the claimed design.
